UNITED STATES PATENT OFFICE.

A. WILLIAM SÜS, OF NEW YORK, N. Y.

KNAPSACK.

Specification forming part of Letters Patent No. 42,805, dated May 17, 1864.

To all whom it may concern:

Be it known that I, A. Wm. Süs, of the city, county, and State of New York, have invented a new and useful Improvement in Knapsacks; and I do hereby declare the following to be a full and exact description of the same, reference being had to the accompanying drawings, making part of this specification, in which—

Figure 1 is a perspective view of a knapsack in a closed condition, illustrating my invention. Fig. 2 is an end elevation thereof. Fig. 3 is an outside view of the knapsack as opened. Fig. 4 is a plan exhibiting the interior construction of the knapsack.

Similar letters of reference indicate corresponding parts in the several figures.

My present invention consists in a novel arrangement of straps, whereby the knapsack, when folded up and applied to the back of the soldier, will be more effectually prevented from causing discomfort and fatigue, and by which the position of the knapsack may be readily varied, so as to shift the weight to different points, and admit of the requisite ventilation, all as will be hereinafter fully explained.

In order that others skilled in the art to which my invention appertains may be enabled to fully understand and use the same, I will proceed to describe it.

In the accompanying drawings, A may represent a knapsack composed of any desired impervious or water proof material, for the purpose of protecting its contents from rain and dampness. B B are the suspending-straps, each of which at one end is securely fastened near the vertical center and bottom of the knapsack A, as shown at b b, (the knapsack being referred to as in a closed condition.) At their opposite ends the straps B B may be made detachable by means of buckles b' b', which are attached at points somewhat lower than the ends b b of the straps B B and nearer the sides of the knapsack. A hook, b², adapted to catch over a corresponding metallic loop, b³, may be employed in lieu of or in addition to the buckles b b, to facilitate the removal and application of the knapsack. B' B' represent short straps, which are also fastened near the bottom and each of the respective sides of the knapsack, and which, together with the straps B B, are securely riveted at b⁴ b⁴ to the knapsack A, the points b⁴ being

located at a distance from the top equal to that which the ends b of the straps B occupy in relation to the bottom. The straps B, being thus attached, will serve to prevent the knapsack from working down to a lower position, retain it in the proper vertical position in which it may be originally adjusted, and effectually obviate the "sagging" and the consequent injurious and fatiguing pressure upon the loins.

The manner of applying the knapsack will be readily understood by reference to Figs. 1 and 2. The knapsack having been placed in the desired position, the straps B B are passed over each shoulder, carried around beneath the armpits, and fastened to the buckles b' b' or loops b³.

C C represent straps which are attached to the front side of the knapsack, but in closer proximity with the top and vertical center thereof than the rivets b⁴ b⁴. The straps B B are provided with hooks b⁵ b⁵, and the straps C C with a series of perforations, in order that when the knapsack is placed upon the upper part of the back of the soldier it may be equally adjusted in position, said straps C C also providing additional means for preventing the knapsack from causing fatigue and discomfort by pressing upon the loins.

D D represent perforated straps which are attached to the back of the knapsack and near each side thereof. By applying these straps D D to the hooks b⁵ b⁵ the knapsack may be turned up into such position as to form a rest or cushion for the musket, for the purpose of relieving the soldier from the direct contact of the arm with his neck or back, the old method being to deposit the arm between the knapsack and the back or neck, which incommodes and imparts an irksome feeling to the soldier, and in some cases produces painful inflammation by chafing. The straps D D also adapt the weight of the knapsack to be either elevated to a higher position or shifted alternately from one shoulder to the other as often as may be desired by the wearer.

E represents a pouch or pocket, which may be made detachable, in order that when the soldier is ordered to march in a light or unburdened condition his goods can be safely packed and left behind.

The haversack and other necessary articles are placed inside of the knapsack, and the

provisions effectually prevented from spoiling by continued rain.

Having thus described my invention, the following is what I claim as new therein and desire to secure by Letters Patent:

1. The suspending straps B B, in combination with the straps C C, the whole being attached substantially as and for the purpose set forth.
2. The straps D D, attached in the manner

described, and employed for varying the position and shifting the weight of the knapsack, as and for the purpose explained.

The above specification of my improvements in knapsacks signed this 15th day of April, 1864.

A. WM. SÜS.
